APPARATUS FOR FINISHING BRAIDED THREADS

Herbert E. Smith, Manchester, N. H., assignor to Wau-Ke-Wan Thread Co., Inc., Manchester, N. H., a corporation of New Hampshire

Application August 17, 1946, Serial No. 691,327

1 Claim. (Cl. 91—17)

This invention pertains to the manufacture of braided thread and more especially to a novel method of and apparatus for use in finishing braided thread. It is customary after the braiding operation to pass the braided thread through a sizing bath or the like and then to dry it, the drying sometimes being followed by a polishing operation. Heretofore it has been usual to wind the thread on a spool as it is delivered by the braiding machine and after the spool is full to cut the braid and carry the spool to the finishing point where the thread is unwound and subjected to the finishing operations. It has also been proposed to deliver the thread directly from the braiding machine to the sizing bath and then to pass it over heated drums or through a baking chamber so as to dry it before rewinding it. This latter procedure employs artificial heat and requires care in the control of the heat and the time of drying in order to insure the desired results without damage to the braid; it necessitates the use of expensive apparatus and the drying apparatus occupies a considerable amount of space which is not always available in the braiding room. The treatment of the thread in spool lengths involves unnecessary labor and loss of time and frequently results in a lack of uniformity in the finished thread.

The principal object of the present invention is to provide a novel method of and apparatus for imparting a desirable finish to a braided thread such that the operation may be carried on uninterruptedly, the thread delivered by the braiding machine being drawn through the sizing bath and finished and dried without resort to artificial heat, and by the use of apparatus which requires but little space and which is relatively inexpensive. A further object is to provide a novel method of and apparatus for finishing braided thread, requiring substantially no attention on the part of the operator and whereby the desired finish is imparted at a minimum cost. A further object is to provide a novel method of and apparatus for use in finishing braided thread whereby substantially uniform results are attained.

In attaining these objects advantage is taken of the fact that if a textile strand of moisture absorbent fiber, for instance cotton or linen, be kept taut during and after its immersion in the sizing bath so that it cannot decrease in length, the moisture absorbed by the strand from the sizing bath evaporates far more rapidly than if the strand be dried in a relaxed state. Thus by keeping a substantial length of the strand

5 (as delivered by the braiding die and while and after passing through the sizing bath) under substantially uniform, high tension while exposed to air at normal room temperature, the strand is quickly and fully dried on its way from the braiding die to the winding spool or beam. Other and further objects and advantages of the invention will be pointed out in the following more detailed description and by reference to 10 the accompanying drawings wherein

Fig. 1 is a fragmentary diagrammatic perspective view showing a conventional braiding machine equipped with the improved finishing apparatus of the present invention;

15 Fig. 2 is a fragmentary diametrical section through a series of pulleys forming a part of the drying means;

Fig. 3 is a similar fragmentary diametrical section through a series of pulleys which cause 20 the thread to advance during the drying operation; and

Fig. 4 is a fragmentary diagrammatic vertical section illustrating means for applying sizing to 25 the thread.

25 Referring to the drawings the numeral 1 designates a conventional braiding machine having a plurality of yarn carriers and having the drive shaft 2 and the braiding die 3 from which the braided strand or thread B is drawn upwardly by means of a take-off and tensioning device. This take-off and tension device is driven by means of a shaft 4 which is actuated by gear connections (not shown) from the shaft 2 and which, through speed reduction gearing, drives the horizontal shaft 5 which carries the tension pulley 6. This pulley or roll 6 is provided with one or more peripheral grooves and the braided strand or thread B is passed about this pulley or roll 6 through a sufficient arc to insure the necessary grip to impart the desired tension to the strand so as to draw it away from the braiding die at the proper speed. From the pulley 6 the strand extends rearwardly and is wrapped about a guide roll 9 mounted upon shaft 10, suitably supported by the frame of the machine. From the pulley 9 the strand extends up in a substantially vertical run 11 and about a grooved pulley 15^x supported to turn freely on a shaft 14 parallel to the shaft 5 and spaced a substantial distance from the latter, for instance a distance of the order of 40 inches. The shaft 14 carries a series of grooved pulleys 15^x, 15^a and 15 (Fig. 2) each provided with a peripheral groove 16, preferably 40 a V-groove. These pulleys are all arranged to 50 55

turn freely on the shaft 14 and independently of one another and are held in proper assembly on the shaft 14 by means of collars or the like secured to the shaft at opposite ends of the series of pulleys.

The shaft 5 which carries the tension roll or pulley 6 also carries a drum 12 provided with a series of peripheral V-grooves 13^a, 13^b and 13 (Fig. 3). This drum is keyed to the shaft 5 to turn with the latter, and if desired the groove 7 of the tension pulley 6 may be formed in this drum 12 rather than in a separate pulley. On the other hand, instead of using the drum 12, the grooves 13^a, 13^b and 13 may be in the peripheries of a series of separate pulleys all of the same effective diameter and all fixed to the shaft 5 so as to turn with the latter.

The braided material of the run 11 engages the first pulley 15^x on the shaft 14 at its front and passes upwardly and rearwardly over this pulley and then downwardly in a run 17 and to the rear of the series of pulleys on the shaft 5 and about a pulley 18 (Fig. 4) mounted to turn freely on a stub shaft carried by a downwardly extending support 19 which is carried by a bracket arm 20 supported by the machine frame. The pulley 18 is located within a suitable reservoir 21 which receives the liquid sizing with which the thread is to be treated. The support 19 carries a second pulley 18^a at a point below the pulley 18, and after leaving the pulley 18 the thread passes down around and in front of the pulley 18^a, then rearwardly about the latter and forwardly about the pulley 18 and then passes up through an eye or slot in a scraper device 22 which removes surplus sizing. It may be noted that the course of the yarn through the sizing bath is such that the one run of the yarn crosses another so as to produce a rubbing action. If desired the yarn or thread may be twisted in its passage through the sizing bath so as to increase the rubbing effect and thus insure proper impregnation with the sizing. After passing up through the eye in the scraper 22 the thread forms the upwardly directed run 17^a which engages the second pulley 15^a on the shaft 14, passing forwardly about this pulley and then downwardly to form a run 24 which passes down and about the second pulley 13^a on the shaft 5. The thread then moves upwardly to form another run which extends up to and about the third pulley on the shaft 14, thence forwardly about the latter pulley and down to wrap about the third pulley 13^b on the shaft 5, etc., forming a series of parallel runs R. The final downwardly moving run 25 is wound on a beam or spool 26 carried by a shaft 27 which is driven by a belt 28 passing about a pulley 29 on the shaft 5.

The pulleys 6, 13^a, 13^b and 13 on the shaft 5 are all of the same effective diameter and as these pulleys have V-grooves they grip the thread firmly so that each run of thread leaving a pulley on the shaft 5 has substantially the same linear speed, this being substantially the same speed as that with which the material is drawn off from the braiding die 3. On the other hand, the pulleys on the shaft 14 are all independent and free to turn so that any bight of yarn extending about one of the pulleys on the shaft 14 is free between its points of tangency with successive pulleys on the shaft 5.

Due to the long extent of yarn exposed between the braiding die and the winding-on spool 26, and by reason of the fact that throughout all

of the length of yarn from the braiding die to the winding-on spool the yarn is held under substantially constant tension, the sizing material is rapidly dried without recourse to the use of artificial heat, the exposure to the air at room temperature being amply sufficient to dry the sizing. This rapid drying under these conditions results from the fact that the yarn is tensioned so strongly that it cannot shrink when wet with the sizing fluid and thus the moisture is very rapidly expelled from the yarn.

A desirable number of pulleys on each of the shafts 5 and 14 is from 10 to 20 and a suitable length of yarn between the braiding die and the winding-on point is 10 yards or more and the speed of rotation of the shaft 5 relatively to the delivery of the braided material is such, as above pointed out, as will prevent any decrease in the length of the yarn while it is passing through the sizing bath and while it is being dried.

Since the drying apparatus is all arranged above the braiding machine it requires little, if any, additional floor space and in a braiding mill having the ordinary head-room it is possible to equip each braiding machine with this improved drying and finishing apparatus without requiring any rearrangement of the braiding machines or any crowding of the machines or a decrease in the number of the machines customarily employed. By this method of procedure the yarn is sized and dried in a continuous uninterrupted operation so that the operation can be performed rapidly and with a minimum amount of labor, and since no artificial heat is employed there is no necessity for care in its control nor danger of injury to the thread by reason of overheating or otherwise. In fact the improved apparatus operates substantially automatically and requires substantially no more attention than the braiding machine itself.

While one desirable embodiment of the invention has been illustrated by way of example, it is to be understood that the invention is broadly inclusive of any and all equivalent arrangements falling within the scope of the appended claim.

I claim:

Apparatus for use in finishing braided yarn 50 as the latter is delivered from the braiding die of a braiding machine, said apparatus comprising: a pull-off roll mounted to receive and engage the yarn as it comes from the braiding die; means for positively driving said pull-off roll at 55 a constant surface speed in definite timed relation to the speed of the braiding machine to impart a predetermined degree of tension to the yarn; a freely rotatable guide roll mounted to receive the yarn from said pull-off roll; a second 60 freely rotatable guide roll mounted to receive the yarn from said first-mentioned guide roll; a receptacle for yarn finishing fluid; yarn guide means within said receptacle for receiving yarn from said second guide roll and immersing the 65 yarn in the fluid; a series of equal-diameter coaxial guide rolls mounted for independent free rotation about an axis spaced from and parallel to the axis of said pull-off roll, the first of said series of guide rolls being positioned to receive the 70 yarn from said yarn guide means; a series of equal-diameter coaxial driven rolls mounted for rotation about the axis of said pull-off roll and driven by said driving means at the same constant surface speed as said pull-off roll, the 75 first of said series of driven rolls being mounted

to receive the yarn from the first of said series of guide rolls, the second of said series of guide rolls to receive the yarn from the first of said series of driven rolls; the second of said series of driven rolls to receive the yarn from the second of said series of guide rolls, and so on in alternation to the end of said series; a winding roll mounted to receive and to take up the braided yarn from the last of said series of guide rolls; and means for positively driving said winding roll at substantially the same surface speed as said pull-off roll, whereby the driving engagement of said pull-off roll and said series of driven rolls at a uniform and constant surface speed thereof imparts a predetermined uniform degree of tension to the yarn throughout the travelling length thereof, transient inequalities

in such tension being immediately equalized by the free rotatability of all of said guide rolls, to thereby accelerate the drying of the yarn at room temperature.
